(57) **CLAIM**

The ornamental design for a device for locking a media disc to a retaining hub, as shown and described.

DESCRIPTION

FIG. 1 is a top plan view of a device for locking a media disc to a retaining hub showing our new design;

FIG. 2 is a perspective view of a device for locking a media disc to a retaining media disc;

FIG. 3 is a top plan view of FIG. 2.

FIG. 4 is a bottom plan view of FIG. 2.

FIG. 5 is a front elevation view of FIG. 3; and,
FIG. 6 is a right side elevation view of FIG. 3.

The broken lines are for illustrative purpose only and forms no part of the claimed design.
